DESIGN FOR A TRUCK BODY

William Elmer Attaway, Sr., Oklahoma
City, Okla.

Application November 17, 1936, Serial No. 65,984

Term of patent 7 years

To all whom it may concern:

Be it known that I, William Elmer Attaway, Sr., a citizen of the United States, residing at Oklahoma City, in the county of Oklahoma and State of Oklahoma, have invented a new, original, and ornamental Design for a Truck Body, of which the following is a specification, reference being had to the accompanying drawing, forming part thereof.

I claim:

The ornamental design for a truck body, as shown.

WILLIAM ELMER ATTAWAY, SR.
